ATTORNEY

UNITED STATES PATENT OFFICE.

ELIZABETH MOREY, OF NEW YORK, N. Y.

COMBINED ELECTRIC LAMP AND GENERATOR.

SPECIFICATION forming part of Letters Patent No. 252,691, dated January 24, 1882.

Application filed January 10, 1881. (No model.)

To all whom it may concern:

Be it known that I, ELIZABETH MOREY, of the city, county, and State of New York, have invented certain new and useful Improvements 5 in Combined Electric Lamps and Generators, of which the following is a specification.

The object of this invention is to furnish a portable electric lamp for domestic and business purposes, which is directly combined with 10 its generator, so as not to be dependent upon a central station for the current, but which may be readily carried from place to place, being about the size of a common table-lamp.

The annexed drawing represents a vertical 15 central section of my electric lamp and generator combined.

A designates the casing or stand of the lamp; C, the generator, and D its motive power. On top of the stand A is mounted the electric 20 burner B, known as an "electric vacuum-lamp," which furnishes the light by the incandescence of a piece of platinum or carbon interposed between the terminal wires of the electric circuit. The piece of carbon or platinum, whichever 25 may be used, between the termini of the circuit-wires, is inclosed in a glass globe, B', which is suitably secured on top of the stand A.

Vertically below the glass globe and light-producer a small dynamo-electric machine or 30 current-generator, C, is arranged inside of the stand A at its upper part. This machine consists essentially of field-magnets, which are rigidly secured to the sides of the stand A, revolving between which is the armature of the 35 machine, connected by arms to a cylinder, C', provided with a commutator, against which current-collecting brushes bear, which brushes are connected directly with the terminal wires of the electric lamp, and are secured to posts fixed 40 to the under side of the top of stand A.

The dynamo-electric machine used may be either a "Gramme," "Siemens," or any other approved electric-current generator operating on the same principle as these.

45 The vertical and centrally arranged shaft or spindle C² of the dynamo-electric machine is

guided in suitable bearings, and bears on its lower extremity a small pinion spur wheel, which is one of a train of wheels in combination with a convolute spring and winding-up 50 devices—a motive power of sufficient power to actuate the current-generator.

It will be seen from the above description that when the motor is wound up it will transmit a rapid rotary motion to the shaft of the 55 dynamo-electric machine, thereby producing currents of electricity, which are directly conducted to the carbon arch or light giving part of the lamp. By establishing the proper relative proportions between the motor, the 60 generator, and the lamp, a reliable compact and portable electric lamp adapted for domestic and other purposes is obtained without the use of a battery.

I claim as my invention—

1. In a portable electric lamp, the combination of a Siemens or other like electric generator, a spring-actuated motor, and an intermediate spindle common to said motor and generator, all inclosed within the stand of the lamp, and 70 a burner on top of the stand, substantially as described.

2. In a dynamo-electric lamp, the combination of a portable stand, an electric burner located at the top of the same, a spring-actuated motor at the base of the stand, a centrally-arranged vertical spindle actuated by said spring-motor, an armature connected to said spindle, a commutator also connected to said spindle, the field-magnets secured to the sides 75 of the stand, the brushes, the posts of which are rigidly fixed to the inside of the stand, and the circuit-wires leading to the carbon arch in the vacuum-globe, substantially as described.

In testimony that I claim the foregoing as 80 my invention I have signed my name, in presence of two witnesses, this 8th day of January, 1881.

ELIZABETH MOREY.
